WASHING MACHINE

George C. Graham, Ridgewood, N. J., assignor, by
mesne assignments, to Graham & Allen, Ridge-
wood, N. J., a limited partnership

Original application November 30, 1939, Serial
No. 306,797. Divided and this application
March 2, 1946, Serial No. 651,498

13 Claims. (Cl. 68—21)

1

My invention relates to washing machines or devices, exemplified herein as applied for household laundry purposes, and particularly to improvements in methods of, and means for, circulating fluids, and conducting them between stationary and movable elements of the machine.

This application is a division of my copending application for Washing Machines, Serial No. 306,797, filed November 30, 1939, now Patent No. 2,407,660.

In devices of this character heretofore suggested, many factors have entered into the problem of rendering them simple, effective, economical and more desirable over a wide field of use, among which are such elements as the particular manner of cleaning and rinsing the clothes, the structure for leading conduit means from a stationary base or housing into an oscillating tub on the base or in the housing, the means for conducting operating fluid to a clothes drying device in the tub, and other features which must be properly combined and operated together to produce a machine that is efficient, easy to use, and free from trouble.

Among the objects of the invention are to provide novel circulation of water, and novel movement of clothes, in a washing machine, whereby to effect better interchange of position of the water and clothes, as between the bottom and top of a tub, to ensure effective cleaning.

Other objects of the invention are to provide a top construction for a washing machine of the upright tub type, that is novel in the provision of a fluid conduit structure for feeding water into the top of the tub, and such structure in which the conduit constitutes substantially a hinge between the tub lid and a housing for the tub.

Another object of the invention is to provide a novel arrangement for supplying fluid for operating a diaphragm within a movable tub, as by providing a conduit between the tub and a stationary base or housing on or in which the tub is disposed, whereby to reduce the over-all height and size of the machine, and to avoid undue flexure of the conduit tending to weaken its connections.

With such objects in view, as well as other advantages which may be incident to a utilization of the improvements, individually or in combination, the invention comprises the elements, steps and combinations thereof herein set forth and claimed, with the understanding that the several necessary elements constituting the same may be varied in proportion, arrangement and texture, without departing from the spirit and scope of the invention as intended, and as set forth in the drawings, specification and claims.

2

In order to render the invention more clearly understood, steps are described, and means are shown in the accompanying drawings for carrying the invention into practical effect, without limiting the improvements to the particular elements shown and described, which for the purpose of explanation, are made the subject of illustration.

In the drawings:

Fig. 1 is a view, partially in elevation and partially in substantially central vertical plane section, of a washing machine of a particular type constructed in accordance with the invention; and

Fig. 2 is a sectional view, taken substantially along the line 2—2 of Fig. 1.

Referring particularly to Fig. 1, the example of the machine therein illustrated comprises a lower base 26, an upper stationary housing 27 on the base 26, an oscillatory tub 28 disposed generally in the housing 27, but having a special top or lid

construction 31 extending above the housing, agitating means 33 having baffles 32 at the bottom of the tub, and baffles 34 near the top of the tub, for agitating the clothes and water in the tub during washing, flushing, and rinsing actions, a dia-

phragm 33 in the tub for effecting flushing and drying actions by expansion of the diaphragm, a valve 36 under the tub for admitting fluid behind the diaphragm and in part controlling operation of the diaphragm 33, a tub oscillating means or

mechanism enclosed in a casing 41 supported by the base 26 under the housing 27, shock absorbing suspension means 42 for the casing 41 associated therewith, and an automatic control mechanism (not shown) mounted on one side of the housing 27.

The base structure 26, has legs 51, at least two of which are suitable in location and construction for cooperation with the shock absorbing suspension means 42. The legs 51 are joined at the lower ends, as by tie rods 53, and suitably support, at the tops, a metal or other disc or plate 56, preferably by means (not shown) for detachably

mounting the legs in position. Casters 54 of the swivel type are provided on the legs 51.

The plate 56 is surmounted by a shell or ring 57 of thin pressed sheet metal having a peripheral top flange 58 for attachment to the housing 27, and a peripheral bottom flange 61 held to the plate 56.

The housing 27 encloses the tub 28, and other parts, and receives wash and rinse water ejected from the top of the tub, as will later appear. A pipe 62, extending from the bottom of the housing through the plate 56, is provided for draining the housing 27. The housing comprises a thin sheet metal lower cup-like portion 63,

having an upper peripheral flange 68 to which is secured an upper thin sheet metal cylindrical member 71. At its upper end, the cylinder 71 is provided with an annular thin sheet metal shell or cap 72 having an offset perimeter 13 secured to the top periphery of the cylinder 71. The remainder of the cap 72 is of substantially half round section, forming a relatively large upwardly convex bead or toroid, having a relatively small radially inwardly extending flange 77 about the upper part of the tub 28 and in closely spaced relation thereto. A bushing 78 is provided in an opening in the shell 72, for a purpose to be hereinafter set forth.

The tub 28 is of the oscillating type for operation about a vertical axis, relative to which its sheet metal body 79 is of somewhat elongated globe shape having a clothes receiving opening at its top, and being shaped at its upper and lower portions for the reception of, and cooperation with, baffle elements of agitator means which will be later described.

The tub has a portion 81 pressed upwardly at the tub bottom. A disc-like metal mounting element 82 is provided outside the tub bottom, and the agitator 83, having a disc-like base 84, is provided inside the tub bottom, these elements also extending about the portion 81, and conforming to and being secured to the tube, as by rivets.

The bottom mounting 82 has a recess for the reception of the upper end of a drive shaft 87 which is operatively connected to the mounting 82, this connection being indicated by a pin 88. The lower portion of the tub also has an aperture in which is secured a bushing 89 in which is received the valve 36, for controlling the diaphragm movements.

At about its vertical central portion the tub 28 is provided with a peripheral channel or bead 92, open at the inner side of the tub and constituting part of means for attaching the diaphragm 33 to the tub, as also will further appear.

The top of the tub has secured thereto a metal casting 96, of cylindrical or ring-like character, having a depending tapered flange 97 conforming, at its outer surface, to the inner surface of the sheet metal body 79 of the tub, and having its inner surface gradually merging and curving into the curved inner surface of the sheet metal body whereby to preserve the gradually rounded inner top contour of the tub. The neck portion of the casting 96 has an outwardly projecting peripheral flange 102, in which is a top groove 103. A plurality of peripherally spaced ducts or outlet ports 106 extend diagonally downwardly and outwardly through the casting 96 from the groove 103 to the exterior of the tub, for allowing water from the tub to drain into the housing 27 through the radially narrow peripheral space between the flange 77, on the shell 72, and the upper part of the sheet metal tub.

The lid 31 comprises a plate 111 constructed of sheet metal pressed to inverted shallow substantially dish shape which, at its periphery, encircles a ring 113, of square cross section, to form a flange that overlies and cooperates with the flange 102. Mounted concentrically with the ring 113 is a frame 132 between which and the plate 111 is disposed a rigid screen 133 conforming in general to the shape of the plate 111. The frame 132 is appropriately secured to the plate, and has peripherally spaced, downwardly extending ducts 134 which communicate at their lower ends with the peripheral groove

103 and at their upper ends with the screen openings.

The screen 133 has radial top grooves or corrugations 135 which when the clothes mass is pressed against the screen by the diaphragm, form gutters or channels for better draining off the water outwardly through the space between the ring 132 and plate 111, downwardly through the ducts 134 into the top annular groove 103, and thence through the ducts 106, into the housing 27, as above mentioned. Before the clothes are tightly pressed against the screen, the main bulk of the wash or rinse water being displaced by the diaphragm flows freely outwardly through various parts of the screen, irrespective of the grooves 135 into the ducts 134 and outwardly from the tub as stated. It should be noted that while the drawings show the ducts 106 and 134 substantially in register, this is not essential, the groove 103 with its ducts 106 being of sufficient capacity to carry off the water admitted to the groove by the ducts 134 irrespective of their locations along the groove.

The lid 31 is removably held upon the tub by a clamping ring 117 of channel section which embraces the lid flange 113 and the tub flange 102, when the lid is in place on the tub. The ring is split, as at one position about its periphery, and provided with operating means for peripheral expansion of the clamping ring to release the lid for opening, and for peripheral contraction of the ring for locking the lid in closed position.

At the top outside center of the lid 31, an aperture therein is surrounded by a nipple 136 attached thereto, on which is a grooved ferrule 137. A cap-like member 138 has a swivel or rotative water sealed connection to the nipple, being provided with a spring clip 143 fitting in the groove of the ferrule and the inner end of which removably extends through an opening in the cap. The cap 138 is connected, by a coupling 139, to a flexible conduit 140 of the metal armored type, relative to which coupling and conduit the nipple oscillates with the tub. The conduit extends through the bushing 78, and between the housing 27 and the tub 28 to a nipple 141 in the bottom wall of the housing. Water is supplied to the conduit 140 from an inlet connection 142, secured to the bottom disc 56, through a hose or conduit 144, which extends through an opening 145 in the shell 57, to a valve of an automatic control mechanism (not shown), and from the valve through a hose or conduit 149, extending through an opening 150 in the shell 57, to the nipple 141, to which the conduit 140 is connected. A source of heated water may be connected to the inlet 142.

A section 151 of the flexible armored conduit 140 acts somewhat as a hinge, or flexible mechanical connector, between the housing 27 and the lid 31, to prevent complete separation of the lid from the tub when the lid is open, and to hold the lid in convenient position for closing the tub. Also, the section 151 of the conduit 140, may move back and forth through the bushing 78 to avoid buckling of the conduit and to better control the action of opening and closing the tub. Furthermore, the flexible connection to the water inlet allows for reciprocation of the tub without damage to the fluid connection.

Although agitation or stirring of the clothes and water may be obtained by agitating means operating relative to a stationary tub, in the

example here given, it is obtained by baffles fixed to the oscillating tub, whereby the water and clothes are given a special tumbling action during washing, indicated somewhat by arrows D; and during rinsing, is combined with, or augmented by, the action of fresh incoming water in the direction of an arrow E, shown at the top of Fig. 1. Either or both sets of baffles 32 and 34 may be employed.

The upper baffles 34 are herein shown as integral parts of the top metal casting 96, although they may be separately attached thereto, or to the tub, or constitute parts of the tub body, and may be varied in number, two being shown, located at opposite sides of the tub. They are of fin-like character rounded at the inner thinner edges 156, and each having a tapered side 157, merging gradually into the inner surface of the tub body, while the opposite side 158 of each baffle is straight, presenting a flat, radially extending side. The flat sides of the baffles 34 face in the same direction with respect to the direction of tub oscillation, for a purpose to be referred to later. The edges 156 slope downwardly and inwardly from the casting 96, substantially as chords of the cross sectional arc of the tub body 79, to a position close to the mid channel 92, where they are suddenly sloped into the tub surface. The broad sides of the baffles extend in a general radial direction to the tub axis at any horizontal section, but longitudinally, they slope relative to the vertical at an angle of about twenty-five degrees.

The lower baffles 32, constituting parts of the agitator 83, are mounted on the disc-like base 84, from the center of which they extend radially. At the upper edge, the baffles are rounded, and the sides divergently tapered laterally to the base. In vertical plane outline the baffles are each of generally curved or rounded contour conforming somewhat to the lower recess of the tub, and having outer enlarged portions 163. These baffles, in relation to such recess and to the globular rising sides of the outer portions of the tub, cause the water and clothes mass to be impelled radially outwardly and upwardly along the sides of the tub, which mass, if uninterrupted, would immediately move downwardly in the center of the tub, round and round. However, at the top, the clothes encounter the agitation produced by the upper baffles 34, which will break up the cycle produced by the lower agitator and keep the clothes well spread out, the over-all agitation being a combination of actions.

The baffles 34, by the lengths and the angular disposition thereof, tend to and do lift the clothes along the baffles, and turn the clothes over, and are of greatest radial depth midway of the length thereof, so that, as the tub oscillates on its vertical axis, the greatest force exerted upon the clothes is radially inwardly along and opposite these mid-sections. However, the sections of the baffles, above the mid-portions, exert a more or less downward component of movement toward and along the axis of the tub, and the sections of the baffles, below the mid-portions, exert a thrust radially inwardly. The result of all of these forces is to cause considerable agitation of the clothes, in the upper portion of the tub, as they are moved inwardly, and before they are carried downwardly in the center.

During rinsing, the central downward movement is augmented by the fresh rinse water entering the tub, in the direction of the arrow E. At the same time, the fresh water is introduced

and mixed in definite and symmetrical manner, ensuring its diffusion to all parts of the clothes mass, and avoiding rinsing more at one part than at another.

In addition to the described actions of the upper baffles 34, they perform a further function in augmenting the thorough cleansing action on the entire clothes mass. Since the tub oscillates on a vertical axis, and the baffles have flat sides facing in the same direction, as these sides move forwardly, they engage the clothes mass and move it part way around the tub circumferentially to occupy a different position with respect to the main forces exerted by the lower baffles. As these baffles move in the reverse direction, the clothes mass slides off the slanting faces thereof. The next forward motion of the flat sides of the baffles engages a different portion of the clothes mass, and thus the clothes are moved around the vertical axis with a step by step motion, in addition to all the other movements imparted thereto.

The tub is oscillated by suitable mechanism, one form of which is shown in my copending application, such mechanism being enclosed in the casing 41 and operatively connected to the shaft 87.

Bolts 288 secure laterally extending plates 291 to the casing 41 at radially opposite parts thereof. The plates 291 are connected to leaf springs 292, of the shock absorber devices 42, which, in turn, are secured to two of the legs 51 of the machine. Near the ends of its strokes, the oscillating structure has its motion damped by the yieldability of the springs 292 in a direction circumferential of the drive shaft, the springs being rigid in the up and down direction.

The diaphragm 33 hereof is made of high grade durable soft rubber, or other material having sufficient weight, body or thickness to be firm and positive in action, and sufficiently flexible to ensure its ready response to expansion and contraction, as well as its ready conformation to the clothes mass whereby to insure uniform effective pressure thereon. It also is molded or formed such that, in its contracted or relaxed state, it conforms closely to the shape of the tub, and also to the baffles 32, and to other parts of the lower agitator.

The diaphragm is somewhat semi-spherical or cup-like in shape, conforming, in general, to the inner lower sides of the tub 28, and having an upper edge peripheral bead 167. An expansion ring 171 engages the upper peripheral part of the diaphragm, just under the bead 167, pressing the same into the channel 92 formed in the tub side wall; this ring having sufficient expansive force to hold the diaphragm securely in place, the arrangement also providing a water tight seal between the diaphragm and tub.

At its bottom, the diaphragm is further provided with portions 168 of inverted substantially channel section closely conforming to, and in relaxed condition fitting over the baffles 32. During expansion, the diaphragm lifts off the bottom of the tub, rising from the baffles and, since it does not turn relative to the tub, returns easily and accurately to position fitting the baffles.

The flow of water, to and from the space between the diaphragm 33 and the bottom of the tub, to expand and contract the diaphragm, is controlled by the diaphragm valve 36. Water under pressure is admitted by the valve 36, through the bushing 39, under or behind the

diaphragm to push or expand the diaphragm upwardly in the tub.

As the clothes are compressed between the diaphragm and the screen 133, the wash or rinse water escapes from the top of the tub, as above described. Near the end of the compressing or drying operation, the pressure behind the diaphragm builds up to that of the incoming fluid. When the water supply has been stopped by the aforesaid automatic control mechanism, a bleeder valve of the valve 36 allows the water pressure in the valve casing to drop gradually. After a certain amount of bleeding, during which the water pressure drops sufficiently in a few seconds, valve 36 opens to the full open position to allow the outflow of water from behind the diaphragm, which action is aided by the contraction of the diaphragm 33. The water flows into the bottom of the housing 27, from which it drains through the drain pipe 62. The water pressure applied behind the diaphragm during expansion of the latter being substantially uniform, the pressure developed in the drying operations are readily calculable, so that the valve 36 may be properly adjusted to effect the desired draining, quickly and in proper sequence.

The pressure maintained by the adjustable bleeder of the valve 36 also enables regulating the duration of the period of high pressures on the clothes, that is to say, the rate of bleeding can be adjusted to determine the length of time before the valve 36 opens to dump the water from behind the diaphragm and, therefore, there may be a period of sustained higher pressures during the drying operation.

The water supply to the valve 36 is from an inlet pipe 214, secured to the disc 56 by a clip 212, through a conduit 216, which extends through an opening 217 in the shell 51, to a valve of the control mechanism. From the latter valve, the water is conducted through a conduit 181, which extends through an opening 182 into the shell 51, the conduit 181 then extending upwardly through a nipple 226 in the bottom wall of the housing 27. It is formed into a flat spiral section 227 (Fig. 2) of about two turns surrounding the drive shaft 87, before continuing to the valve 36. The turns of the spiral are of relatively large diameter and adapted to radially contract and expand so that the tub may oscillate without adversely affecting the fluid connections by reason of the relative movement between the tub carried valve 36 and the stationary nipple 226. Arranging the conduit section 227 in a flat spiral coil, also allows the bottom of the tub to be spaced from the bottom of the housing by a minimum distance, whereby to conserve space at a place where such conservation is of importance in a selection of height for the housing. The conduit section 227 may be arranged otherwise, such as to bend on a substantial radius or radii to effect substantially equivalent results.

Special provisions are made to insure complete draining of the water from behind the diaphragm 33, and to insure against accidental and premature closing of the opening to the diaphragm valve. To this end, the lower face of the base 84 of the lower agitator has an annular groove 228, having a peripheral portion 229. The head of the mounting bushing 89 for the diaphragm valve 36 is received in the groove 228. The base 84 has apertures 234 therethrough communicating with the groove 228, and the peripheral portion 229 also has apertures 232 communicating with the groove 228. When water is admitted behind the

diaphragm, it passes through the apertures 234 and 232 to start the diaphragm expansion. When the water is being expelled from below the diaphragm, it drains through the apertures 232 and 234 into the groove 228 and from the latter through the valve 36 to the tub housing 27, but without danger of the diaphragm fouling the opening into the diaphragm valve 36.

At the beginning of the operation of the machine, the operator places the dry clothes in the tub. The machine is next filled with water and soap, washing powder or water softener added, after which the lid 31 is locked in place.

The drive mechanism is energized to oscillate the tub to produce agitation of the clothes and water. At the end of a selected washing time period, the automatic control mechanism may operate to admit water behind the diaphragm 33, through the valve 36, to begin a flushing operation, in which the diaphragm lifts the clothes and wash water toward the top of the machine so that the wash water is gradually forced out through the drain openings 134, in the lid, and the opening 106, in the tub. Thus, any scum and matter which has accumulated on top of the water is flushed out of the machine. At this time, the agitation of the machine has not stopped, so that the accumulated matter also is liberated from the clothes to float off with the water.

Inflation of the diaphragm may continue, until substantially all of the wash water has been extracted from the clothes at which time the valve 36 operates to empty the water from behind the diaphragm, and the diaphragm returns to its lower position shown.

By this time, the control mechanism operates to admit water to the upper part of the tub, as through the center of the lid to begin the rinsing operation. When sufficient water has been admitted to the tub to make agitation of the clothes and water of some benefit, which is about one-third of the time consumed by the rinsing operation, agitation is re-started. Agitation continues during the remainder of the rinsing operation, and for a sufficient length of time for the tub to completely fill with water and also to overflow through the ducts 134 and 106 for a sufficient interval to thoroughly rinse the clothes.

At the conclusion of the rinsing operation, the control mechanism again opens the diaphragm water valve to again expand the diaphragm to eject the rinse water, which is the beginning of the drying operation. Agitation is continued further until the diaphragm is above the center of the tub, and preferably during about half of the period of time for this particular operation of the diaphragm. The expansion of the diaphragm continues to bring about drying of the clothes by compressing the same against the upper portions of the tub and its cover, until all of the water is extracted from the clothes whereupon the supply of water behind the diaphragm is shut off. Then, the action of the diaphragm valve 36 will again operate to dump the water from behind the diaphragm, as explained above.

Other modifications may be made in the arrangement and location of parts within the spirit and scope of my invention, and such modifications are intended to be covered by the appended claims.

I claim:

1. In a washing machine, a tub support, a tub mounted on said support for oscillation relative thereto about a vertical axis, a top lid mounted

on the tub for oscillation therewith and for movement relative thereto for opening and closing the tub, and water conduit means including a conduit element fixed to said lid and a flexible conduit element connected to said support and acting substantially as a hinge between said support and the lid, said flexible conduit also being connected in relatively movable sealed relation to said first conduit.

2. In a clothes washing machine, the combination of a stationary base having a conduit mounting, an oscillating tub mounted on said base and having a port, fluid operated means in the tub for receiving fluid from said port for pressing the clothes to extract water therefrom, and a conduit for transmitting fluid between the exterior of the tub and said pressing means having portions mounted relative to said base and relative to said tub in communication with said port, respectively, said conduit including portions wound about the axis of oscillation of the tub in a coil of such diameter as to render flexing of the conduit next to said port and said base substantially negligible.

3. In a clothes washing machine, the combination of a stationary base having a conduit mounting, an oscillating tub mounted on said base and having a port, fluid operated means in the tub for receiving fluid from said port for pressing the clothes to extract water therefrom, and a conduit for transmitting fluid between the exterior of the tub and said pressing means and having portions respectively connected to said base mounting and to said tub in communication with said port, said conduit including intermediate portions wound about the axis of oscillation of the tub in a substantially flat spiral normal to said axis.

4. In a washing machine, the combination of a stationary housing having a top opening and upper and lower conduit receiving apertures, a tub mounted in said housing for oscillation about an upright axis and having a top cover opening aligned with said top housing opening, and flexible water conduit means extending through said lower aperture, upwardly in the housing between the housing and the tub, through said upper aperture, and being connected to an upper portion of the tub for the admission of water into the tub above said housing.

5. In a washing machine, the combination of stationary supporting means, tub means mounted on said supporting means for oscillating movement relative thereto, and means for supplying water to said tub and including conduit mounting means on said supporting means, conduit receiving means carried by said tub means for oscillation therewith, and conduit means extending between said mounting means and said receiving means and having an intermediate portion arranged in the form of a spiral to permit said oscillation.

6. In a washing machine, the combination of stationary supporting means, tub means mounted on said supporting means for oscillating movement relative thereto, a plurality of conduit mounting means on said supporting means, a plurality of conduit receiving means carried by said tub means for oscillation therewith, flexible conduit means extending between each of said mounting means and said receiving means and permitting said oscillation, and fluid supply means connected to said conduit mounting means.

7. In a washing machine, the combination of

stationary supporting means, tub means mounted on said supporting means for oscillating movement relative thereto, conduit mounting means on said supporting means, a plurality of conduit receiving means carried by said tub means for oscillation therewith, conduit means extending between said mounting means and each of said receiving means and permitting said oscillation, and fluid supply means connected to said conduit mounting means.

8. In a washing machine, the combination of stationary supporting means, tub means mounted on said supporting means for oscillating movement relative thereto, a plurality of conduit mounting means on said supporting means, a corresponding plurality of conduit receiving means carried by said tub means for oscillation therewith, conduit means extending from each of said mounting means to a corresponding receiving means and permitting said oscillation, and fluid supply means connected to said conduit mounting.

9. In a washing machine, the combination of stationary supporting means, tub means mounted on said supporting means for oscillating movement relative thereto, conduit mounting means on said supporting means, conduit receiving means carried by said tub radially offset from said conduit mounting means relative to the axis of oscillation, conduit means extending between said mounting means and said receiving means and permitting said oscillation, second conduit mounting means on said supporting means, second conduit receiving means carried by said tub offset from said second mounting means along said axis, conduit means extending between said second mounting means and said second receiving means, and fluid supply means connected to said conduit mounting means.

10. In a washing machine, a housing, a tub mounted therein, separate agitating means in the upper and lower parts of the tub for agitating clothes and water in the tub, a fluid means for operating said agitating means, operated diaphragm mounted upon the tub and arranged to compress the clothes in the tub to extract water therefrom, means for supplying water to the tub so as to direct the water downwardly into said tub, and means connected to the tub for supplying water behind the diaphragm to cause the same to compress the clothes and also to remove the water from behind the diaphragm after the compressing operation.

11. In a washing machine, a housing, a tub mounted for oscillation therein, separate agitating means in the upper and lower parts of the tub for agitating clothes and water in the tub, a fluid operated diaphragm mounted upon the tub and arranged to compress the clothes in the tub to extract water therefrom, means connected to the tub for supplying water to the tub so as to direct the water downwardly into said tub, means connected to the tub for supplying water behind the diaphragm to cause the same to compress the clothes, and flexible connections to each of said water supply means arranged to permit the oscillations of said tub.

12. In a washing machine, a support, a tub mounted on said support, means for oscillating the tub, a flexible diaphragm mounted in the tub, and means for supplying water to the interior of said tub, said latter means including stationary conduit elements connected to and communicating with the interior of the tub above and below

said diaphragm and separate flexible conduits connected to each of said stationary conduits and also to said support, said conduits extending spirally between said points of connection.

13. In a washing machine, a support, a tub mounted on said support, means for oscillating the tub, a stationary conduit connected to and communicating with the interior of the tub, a conduit connected to the first mentioned conduit, and a swivel connection between said conduits providing for said oscillation.
